UNITED STATES PATENT OFFICE.

ADOLPH SCHRÖDER, OF BERLIN, GERMANY, ASSIGNOR TO ALFRED KRAUSE, OF BERLIN, GERMANY.

DRYING-CHAMBER.

No. 822,990.

Specification of Letters Patent.

Patented June 12, 1906.

Application filed August 30, 1905. Serial No. 277,278.

To all whom it may concern:

Be it known that I, ADOLPH SCHRÖDER, a subject of the King of Prussia, and a resident of 5 Teltowerstrasse, Berlin, in the Kingdom of Prussia, German Empire, have invented new and useful Improvements in Drying-Chambers, of which the following is a specification.

My invention relates to an improved drying chamber or closet, the essential feature of which is that the hot air employed for effecting drying flows into the chamber through its side walls and door, passes around the objects to be dried, and then escapes through the outlet-flue or chimney of the chamber.

The invention is illustrated in the accompanying drawings, in which—

Figure I is a vertical section of the apparatus. Fig. I^a is an elevation of the door, partly in section. Fig. II is a vertical section taken at right angles to Fig. I. Fig. III is a horizontal section through Fig. I. Fig. IV is a plan of one of the trays. Fig. IV^a is a section through Fig. IV. Fig. V is a plan view illustrating the manner of disposal of the gas-pipes. Fig. VI is a plan of the heating-box. Fig. VI^a is a front elevation thereof. Fig. VI^b is a side elevation thereof. Fig. VII is a detail sectional view drawn to an enlarged scale and showing the manner in which the gas-pipes are secured below the heating-box.

The drying-chamber consists of the lower portion 5, in which the hot air for drying is produced, and the main portion or actual drying-chamber, which is surrounded by hollow side walls 1 2 3 and a hollow door 4.

Both the hollow side walls 1 and 2 and the hollow door 4 are provided on the inner and outer walls with sliding dampers 24 25 26 27 33 34, having a number of perforations, so that by opening the inside dampers only the hot air employed for drying rushes directly into the interior chamber or oven, while by opening the outside dampers located opposite these inside ones tempered air streams into the oven. By the provision of such dampers at various heights it is thus possible to introduce hot or tempered air to each zone of the drying-chamber, as desired.

The articles to be dried are placed upon the drying-trays 37, Fig. IV, and after the chamber-door has been opened are pushed onto ledges 35. These latter are of angle-

iron of U shape and their limbs, Fig. III, are secured to the face of the side walls of the drying-chamber, while the third portion or base of the U stands at a certain distance from the back wall of the chamber and serves as a stop to prevent the trays from being pushed in too far. In this manner even large objects can be placed in the drying-chamber. Owing to the distance between the ledges and the back wall of the chamber, the vapors arising during the drying process can pass off unobstructedly.

The hot-air generating apparatus 5, Figs. I and VI, consists of two parts—a bottom compartment 6 and an upper compartment 7. The former lies directly above the gas-pipes 20 21 22 23 and is provided on the right and left and in front with sliding dampers 45 46 19, having each a number of perforations through which cold air can flow in. By a suitable arrangement of baffle-plates, Fig. I, 75 in the said bottom part the air is always brought to the hottest parts of the base and then flows through the apertures 15 16 17, Fig. VI, into the distributing-compartment 7, where it is compelled by ribs 8 9 10 11 to 80 flow, on the one hand, to the hollow side walls 1 and 2 through the apertures 12 14 and, on the other hand, to the hollow double doors 4, Figs. II and VI, through the apertures 13. The place 47, at which the hot air rushes into 85 the hollow double door 4, is provided with a sliding damper 48, presenting a number of perforations, whereby when the door is opened by operating this damper hot air may be prevented from escaping.

The method of arranging the gas-pipes 20 to 23 below the heating-chamber 5 is illustrated in detail in Fig. VII. The pipes 20 to 23, which are furnished with two rows of gas-outlet holes, are adjustably supported by 95 screw-holders 38 and lie directly below the ridges or elevations 40 40, presented by the bottom of the heating-chamber 5. There is thus a space 43 left above the pipe, through which (since the gas-pipes are somewhat inclined in position) the vapors and heating-gases arising in combustion will readily flow off toward the hollow back wall 3. By this means, first, the cold air at 41 42 can readily flow along the entire length of the gas-pipe, 100 and, second, the rearwardly-lying gas-jets are prevented from burning badly or failing to burn at all.

As Fig. V shows, the gas-pipes are so arranged that those lying toward the center are shorter than the outer ones. The line 39 indicates the position of the front edge of the 5 drying-chamber.

In the center of the hollow double door 4 there is a horizontal partition 32, from which two vertical partitions 30 31 run downwardly at the right and left, so that the air leaving 10 the heating-box 5 is caused to flow directly to the top part of the door when the lower dampers are closed.

In the actual heating-chamber between the 15 ribs coarse metallic turnings, borings, or like shavings may be introduced for the purpose of increasing the surface. Such turnings or the like may also be introduced into the hollow side walls and double door to serve as filter. 44 is the chimney or outlet flue for 20 spent air and vapors and waste gases.

Having thus described my invention, I claim as new and desire to secure by Letters 25 Patent—

1. A drying apparatus, comprising a chamber having hollow walls, the inner walls presenting hot-air inlets and the outer walls cold-air inlets at parts coincident with the hot-air inlets, perforated slides controlling such air-inlets, means at the bottom of the 30 apparatus for heating the air which passes between the chamber-walls, and a spent-air and waste-gas outlet, substantially as described.

2. A drying apparatus, comprising a chamber having a hollow-walled body and door, the inner walls of which body and door present hot-air inlets and the outer walls cold-air inlets at parts coincident with the hot-air inlets, perforated slides controlling such inlets, means at the bottom of the apparatus 35 for heating the air, which passes between the chamber-walls, and a spent-air and waste-gas outlet, substantially as described.

3. A drying apparatus, comprising a chamber having a hollow-walled body and door, the inner walls of which body and door present hot-air inlets and the outer walls cold-air inlets at parts coincident with the hot-air inlets, perforated slides controlling such inlets, a horizontal perforated partition dividing 40 the space between the door-walls and two vertical partitions extending downward from the horizontal partition, means at the bottom of the apparatus for heating the air

which passes between the chamber-walls, 55 and a spent-air and waste-gas outlet, substantially as described.

4. A drying apparatus, comprising a chamber having a hollow-walled body and door, the inner walls of which body and door present hot-air inlets and the outer walls cold-air inlets at parts coincident with the hot-air inlets, perforated slides controlling such inlets, superposed horizontal U-shaped frames secured to the inner side walls of the chamber, the base of the U standing free of the back wall, and trays adapted to lie on the frames, means at the bottom of the apparatus for heating the air which passes between the chamber-walls, and a spent-air and waste-gas outlet, substantially as described. 60 65 70

5. A drying apparatus, comprising a chamber having a hollow-walled body and door, the inner walls of which body and door present hot-air inlets and the outer walls cold-air inlets at parts coincident with the hot-air inlets; perforated slides controlling such inlets, a heating-box at the bottom of the apparatus communicating with the spaces between the said body and door walls and presenting an upper distributing-compartment and a lower air-heating compartment communicating therewith and having cold-air inlets and an inclined ridged base; and gas-pipes presenting laterally-directed jet-holes, 85 located below the ridges in such a manner, that a space is left above the jets; and a spent-air and waste-gas outlet, substantially as described. 75 80 85

6. A drying apparatus, comprising a chamber having hollow walls, the inner walls presenting hot-air inlets and the outer walls cold-air inlets at parts coincident with the hot-air inlets, perforated slides controlling such air-inlets, means at the bottom of the 90 apparatus for heating the air which passes between the chamber-walls, metallic shavings packed in the space between the walls and a spent-air and waste-gas outlet, substantially as described. 95 100

In testimony whereof I have signed my name to this specification in the presence of two subscribing witnesses.

ADOLPH SCHRÖDER.
